WILLIAM A. JONES, OF WESTERLEIGH, NEW YORK, ASSIGNOR TO THE BABCOCK & WILCOX COMPANY, OF BAYONNE, NEW JERSEY, A CORPORATION OF NEW JERSEY

FURNACE AND BOILER

Application filed November 21, 1929. Serial No. 408,746.

This invention relates to a furnace above which a boiler is located, the walls of the furnace and the boiler proper being so disposed as not to interfere with each other 5 when expansion and contraction takes place.

The invention will be understood from the description in connection with the accompanying drawings in which Fig. 1 is a vertical section through an illustrative embodiment of the invention; Fig. 2 is a section through a side wall of the furnace taken along the line 2—2 of Fig. 1; Fig. 3 is a section on an enlarged scale at the upper end of the rear wall of the furnace; Fig. 4 is a 10 section taken along the line 4—4 of Fig. 3; Fig. 5 is a section on an enlarged scale at the upper end of the front wall of the furnace; Fig. 6 is a section taken along the line 6—6 of Fig. 5; Fig. 7 is a section on an enlarged scale at the upper end of a side wall 15 of the furnace; and Fig. 8 is a section taken along the line 8—8 of Fig. 7.

In the drawings, reference character 1 indicates a furnace that may be fired by means 20 of the stoker 2.

A boiler of the Babcock & Wilcox type is located above the furnace and comprises the usual steam and water drum 3, downtake headers 4, uptake headers 6, nipples 5, circulating tubes 7, banks of inclined tubes 8 and 9 and baffles 10 for directing the gases from the furnace across the banks of tubes 8 and 9 and into the outlet 11.

A pipe 12 connects the steam space of the 35 steam and water drum 3 to the inlet header of the superheater 13. The outlet header of the superheater is indicated at 14. The superheater is located between the banks of tubes 8 and 9 and is supported upon the 40 boiler parts. A support 15 for the superheater is shown resting upon the upper row of inclined tubes 8.

A transverse support 16 is provided near the upper end of the rear wall of the furnace 45 with a plate 17 resting upon this support. Supporting members 18, provided with curved supporting shoulders 19, rest upon the plate 17 and support the upper curved ends of the furnace wall tubes 20 in the rear wall of the furnace. The tubes 20 extend into

an upper header 21 that rests upon a saddle 22 that is supported upon the brackets 23 on the support 16, the U-bolts 24 retaining the header 21 in place. Tile 25, such as Bailey blocks, for example, are connected 55 to the tubes 20.

The lower ends of the tubes 20 extend outwardly and are connected to the lower header 26 and may be supported in part by means of the spring supports 27 from the transverse 60 support 28. The headers 21 and 26 may be connected to the circulation system of the boiler and to each other by means of tubes 30 in the usual way.

A channel 29 extends across the supporting 65 members 18 and rests thereupon. The lower ends of the headers 6 and the corresponding wall of the boiler proper rest upon the channel 29 and are thereby supported at the bottom so that the parts will expand upwardly. 70 The furnace wall expands downwardly and is supported by the same support as the corresponding wall of the boiler.

A transverse support 31 is provided near the upper edge of the front wall of the furnace. 75 A plate 32 rests upon the support 31. Supporting members 33, similar to the supporting members 18, rest upon the plate 32 and support the upper outwardly curved ends of the furnace wall tubes 34 that extend into the header 35. The header 35 is supported by a saddle 36 that is in turn supported by the support 31 and the I-beam 37, U-bolts 38 holding the header 35 in place in the saddle 36. 80

The lower ends of the tubes 34 extend outwardly into the lower header 39 and the lower portions of the tubes 34 may be connected to and supported by the I-beams 39. Tile 40, such as Bailey blocks, for example, 90 are connected to the tubes 34. Tubes 41 may connect the headers 35 and 39 to each other and to the circulation system of the boiler in the usual way.

A channel 42 extends across the supporting 95 members 33 and is supported thereby. The lower ends of the downtake headers 4 or the mud drum 4' rest upon the channel 42 and are supported thereby, together with the corresponding wall of the boiler so that the parts 100

will expand upwardly. By supporting the boiler parts at the bottom, so that they will expand upwardly and locating the superheater in the position described, so as to be supported by the boiler parts, the superheater will not be moved up and down appreciably, due to expansion of the boiler parts, so that the connection of the outlet header 14 of the superheater to the steam mains will not be seriously interfered with by the slight movement due to expansion and contraction.

A transverse support 45 is provided at each side of the side walls of the furnace near their upper edges. A plate 46 rests upon this support 45. Supporting members 47 with inclined shoulders 48 for the upper outwardly inclined portions of the furnace wall tubes 49 rest upon the plate 46. The tubes 49 extend into a header 50 that is supported by the supporting members 47. Tile 51, such as Bailey blocks are connected to the tubes 49. Boxes 52 above the header 50 rest upon the supports 47 and blocks 55 at the lower edge of the side wall 56 of the boiler rest upon the boxes 52 and are thereby supported by the support 45.

Blocks 57, 58 and 59 may be installed above the curved portions of the tubes 20, 34 and 49 to close the spaces between the corresponding parts of the furnace walls and the boiler parts.

The lower headers 26 of the front and rear walls and the lower header 53 of the side walls of the furnace are each arranged so that they can move downward with expansion of the furnace wall tubes when the headers to which the upper ends of these tubes are connected are fixed in position.

I claim:

1. In combination, a boiler, a furnace below said boiler, metallic supporting means at the lower portion of said boiler and the upper portion of said furnace walls, said boiler having metal parts resting upon said supporting means and said furnace walls having metal parts suspended from said supporting means.

2. In combination, a boiler, a furnace below said boiler, metallic supporting means at the lower portion of said boiler and the upper portion of a wall of said furnace, said boiler being supported upon said supporting means by having metallic parts thereof resting upon said supporting means, and said furnace wall having metal parts suspended from said supporting means, said boiler and said furnace being in substantially fixed relation at said supporting means.

3. In combination, a boiler, a furnace below said boiler, metallic supporting means at the lower portion of said boiler and the upper portion of a wall of said furnace, said boiler being supported upon said supporting means by having metallic parts thereof resting upon said supporting means, and said furnace wall having fluid cooled metal tubes suspended

from said supporting means, said boiler and said furnace being in substantially fixed relation at said supporting means.

4. In combination, a boiler, a furnace below said boiler, metallic supporting means at the lower portion of said boiler and the upper portion of a wall of said furnace, said boiler being supported upon said supporting means by having metallic parts thereof resting upon said supporting means, and said furnace wall having metal parts suspended from said supporting means, said boiler and said furnace being in substantially fixed relation at said supporting means, said supporting means having supporting surfaces for the metallic parts of said boiler and furnace.

5. In combination, a boiler, a furnace below said boiler, metallic supporting means at the lower portion of said boiler and the upper portion of a wall of said furnace, said boiler being supported upon said supporting means by having metallic parts thereof resting upon said supporting means, and said furnace wall having fluid cooled metal tubes suspended from said supporting means, said boiler and said furnace being in substantially fixed relation at said supporting means, and said supporting means having supporting surfaces for the metallic parts of said boiler and said fluid cooled tubes of said furnace.

6. In combination, a boiler provided with vertically disposed headers, a furnace below said boiler, metallic supporting means at the lower portion of said boiler and the upper portion of a wall of said furnace, headers of said boiler having their lower ends supported by said supporting means by having metallic parts thereof resting upon said supporting means, and said furnace wall having fluid cooled metal tubes suspended from said supporting means, said boiler and said furnace being in substantially fixed relation at said supporting means.

WILLIAM A. JONES.
